UNITED STATES PATENT OFFICE.

AUGUST N. CRAMER, OF BROOKLYN, NEW YORK, ASSIGNOR TO COLUMBIA MACHINE WORKS & MALLEABLE IRON CO., OF BROOKLYN, NEW YORK, A CORPORATION OF NEW YORK.

GEAR-CASE.

1,292,265.

Specification of Letters Patent. Patented Jan. 21, 1919.

Application filed July 18, 1918. Serial No. 245,479.

To all whom it may concern:

Be it known that I, AUGUST N. CRAMER, a citizen of the United States, residing in the borough of Brooklyn, county of Kings, city 5 and State of New York, have invented an Improvement in Gear-Cases, of which the following is a specification.

This invention relates to that type of gear cases employed in connection with motor vehicles and more particularly with motor vehicle trucks. In the use of gear cases heretofore commonly employed in this type of vehicle trucks, much difficulty has been experienced in the breaking of the gear cases 10 at the points at which they are mounted in the truck, due primarily as will be understood, to the torsion and other strains placed on the gear cases at their points of connection in the vehicle. The object of the present invention therefore is to overcome this difficulty by producing a gear case in which the parts of support are so designed as to increase the strength of the same to a maximum and consequently reduce the liability 15 of breaking by torsion or strains to which they are subjected to a minimum, and the gear case made in accordance with my present invention will be hereinafter more particularly described.

30 In the drawing:

Figure 1 is a front elevation of one member of a gear case made in accordance with this invention.

Fig. 2 is an inverted plan view of the same. 35 Fig. 3 is an end elevation of the left hand end of the gear case member as shown in Fig. 1.

Fig. 4 is a partial elevation of a gear case illustrating a modified form of the invention, 40 and

Fig. 5 is an end elevation of the form of gear case illustrated in Fig. 4.

Referring to the drawing, and particularly to Figs. 1, 2 and 3, the gear case comprising this invention is made in parts, one of which is shown in these figures, and each part consists in side members 10 and 11 made in the required size and shape and of any suitable metal. These side members 10 45 and 11 at their ends are preferably turned inwardly or toward each other and caused to abut against one another, the end members of the side 10 being indicated at 12 and the end members of the side 11 being indicated at 13. Together with the side members 10 and 11 I employ a cover 14. 50

At its edges the cover is flanged at 15 for a predetermined distance, and these flanges fit over the adjacent edges of the side members 10 and 11 and are secured thereto by 60 rivets 15' or otherwise.

The construction at the ends of each member of the gear casing is substantially similar. Referring however to the left hand end of the part of the gear casing shown in Fig. 1 it will be seen that the flange 15 terminates an appreciable distance short of the end of the cover 14 and at its extremity the cover 14 is provided with a flange 16 which is turned outwardly or on an opposite 65 direction to the flange 15, and between the ends of the flange 16, the cover 14 terminates in a support member 17. Associated with this end of the gear case I employ a bracket. This bracket comprises side members 18 and 19, a front member 20 adapted to lie against the outer faces of the adjacent ends 12 and 13 of the side members 10 and 11. Forming a part of this bracket there is also a support plate 21 adapted to underlie the support plate 17. Fitting between the support plates 17 and 21 there is an insert plate 22. This insert plate may be made of the same or a material of different tensile strength to the other parts of the gear case, and is 70 preferably flanged as indicated at 23, these flanges lying against the adjacent surfaces of the side members 18 and 19. It will be noted that the side plates 18 and 19 extend an appreciable distance beyond the cover 14 75 and this extended portion is indicated at 24. The support plates 17 and 21 with the intervening insert plate 22 are secured to one another by rivets 25 or otherwise, and preferably centrally these parts are also 80 fitted with a bolt hole 26. The flanges on the insert plate 22 are secured to the side members 18 and 19 of the bracket by rivets 27 or otherwise, and the side plates 18 and 19 are secured to the side members 10 and 11 85 by rivets 28 or otherwise. Furthermore the front plate 20 may be connected to the in-turned ends of the side members 10 and 11 by rivets 28' or otherwise. The side plates 18 and 19 and the adjacent portions of the side members 10 and 11 may be recessed as indicated at 29 to receive the drive shaft and parts connected thereto, while as clearly indicated in Figs. 1 and 2, the side members 10 and 11 may be recessed as indicated at 100 30 so as to fit over the axle of the vehicle.

The construction at the other end of this

gear case member is substantially the same as that hereinbefore described with the exception of the shape and dimensions of the side members of the bracket, one of which on this 5 end of the gear case part is indicated at 18'.

As will be understood and as hereinbefore intimated, the duplicate of the member hereinbefore described is associated therewith in completing the gear case, and these parts 10 are connected to and supported by cross members in the chassis of the vehicle truck, bolts or other means passing through the bolt holes 26 for securing the parts in position.

15 Referring to Figs. 4 and 5 it will be seen that the side members of the part of the casing are indicated at 31 and 32, the cover is indicated at 33, and this is provided with flanges 34 secured to the sides 31 and 32 20 by rivets 34' or otherwise. In this construction the cover 33 extends beyond the flange 34 as indicated at 35, and terminates in a support plate 36 in substantially the same manner as the cover 14 as illustrated in the 25 preferred form of the invention. In this construction however, instead of employing separate independent brackets as described in the preferred form of the invention, the ends of the side members 31 and 32 may be 30 extended as indicated at 37 and 38. The extremity of the cover 33 is flanged as indicated at 39 and 40, these flanges bearing respectively against the inner surfaces of the side member extensions 37 and 38. In this 35 form of the invention I employ an insert plate indicated at 41 lying against the support plate 36 and connected thereto by rivets 42 or otherwise. This insert plate has an upwardly extending portion 43 which 40 forms to and lies against the end of the cover 33 within the flanges 39 and 40. The extremity 36 of the cover 33 and the insert plate 41 may be provided with a bolt hole 44 by which these parts are connected to 45 position with the cross pins of the chassis of the vehicle truck.

Now as will be readily understood, the strength of the support members of the gear case as made in accordance with this invention will be such as to withstand the ordinary tensile and other strains to which the same are subjected in the use of the vehicle.

I claim as my invention:

55 1. In a gear case part, sides, a cover having inturned flanges to which the sides are secured and outturned flanges at its extremities, a support member extending between the outturned flanges at the end of the cover, 60 and a reinforcing member secured to the said support member.

2. In a gear case part, sides, a cover hav-

ing inturned flanges extending for a portion of its length and to which the said sides are secured and outturned flanges at the end 65 thereof, a support member extending between the outturned flanges at the end of the said cover, and a bracket comprising side members, a front member, and a support plate secured to the said support member 70 at the extremity of the said cover.

3. In a gear case part, sides, a cover having inturned flanges extending for a portion of its length and to which the said sides are secured and outturned flanges at the 75 end thereof, a support member extending between the outturned flanges at the end of the said cover, a bracket comprising side members, a front member, and a support plate, an insert member between the said 80 support member and support plate, and means for securing together the said support member, support plate, and the intervening insert member.

4. In a gear case part, sides, a cover having inturned flanges extending a predetermined part of its length and to which the said sides are connected and outturned flanges at the end of the said cover, a support member at the extremity of the cover 90 extending between the outturned flanges thereof, a bracket comprising side members secured to the aforesaid sides, a front member, and a support plate, an insert member lying between the said support member 95 and support plate and having flanges secured to the side members of the bracket, and means for connecting the said support member, support plate, with the intervening insert member.

5. In a gear case part, sides which at their extremities are inturned and cause to abut against one another, a cover having inturned flanges extending for a predetermined portion of its length and to which the said sides are connected, the said cover also having at its extremity outturned flanges, a support member at the end of the cover and extending between the said outturned flanges, a bracket comprising side members secured to the said sides of the gear case part, a front member lying against and secured to the inturned ends of the said sides, and a support plate lying beneath the said support member at the 115 end of the cover, an insert member lying between the said support member and support plate and having outturned flanges which are secured to the side members of the bracket, and means for securing together 120 the said support member, the support plate with the intervening insert member.

Signed by me this 19 day of June, 1918.
AUGUST N. CRAMER.
